BACKGROUND SCREEN FOR PHOTOGRAPHERS AND THE LIKE

Arnold Bert Coleman, Chicago, Ill.

Application November 22, 1943, Serial No. 511,217

2 Claims. (Cl. 160—24)

My invention relates to improvements in background screens for use especially, although not necessarily, by amateur photographers.

The principal object of my invention is to provide a light weight, readily portable and collapsible apparatus of simple construction whereby different types of photographic screens may be quickly erected indoors for use selectively in indoor photography to lend a professional touch to amateur photographs and which may be easily conditioned for carrying or storage.

Another object is to provide apparatus of the character and for the purposes above set forth which provides a moving picture screen for motion pictures and which can be used for still pictures.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in perspective of my invention, in its preferred embodiment, the box being closed.

Figure 2 is a view in top plan with the lid of the box open.

Figure 3 is a view in bottom plan.

Figure 4 is a view in front elevation with one of the screens unrolled and erected.

Figure 5 is a view in end elevation.

Figure 6 is a view in vertical transverse section taken on the line 6—6 of Figure 4 and drawn to an enlarged scale.

Figure 7 is a view in longitudinal section of one of the supports, and

Figure 8 is a view in transverse section illustrating the manner in which one of the screens is attached to one of the supports.

Referring to the drawings by numerals, my invention in its preferred embodiment comprises a foundation, or base, structure having the form of an elongated narrow box 1 provided with a lid 2 hinged to one side wall 3 of the box, as at 4, and provided with a suitable catch 5 for cooperation with a complementary catch member 6 on the other side wall 7 of said box. A pair of brace bars 8 are provided upon each side of the transverse center of the box 1 with ends pivoted, as at 9, to the bottom 10 of said box so that the bars in each pair may be swung to extend oppositely from opposite sides of said box and brace the latter against upsetting, or, said bars may be 55

swung under said bottom into out-of-the-way position when not in use. The box 1 is provided with a handle 11.

5 A pair of tubular rollers 11, 12, respectively, are provided in the bottom of said box 1 to extend substantially from end to end of the box in spaced-apart relation and parallel with each other and with the side walls 3, 7. The rollers 11, 12 are provided with suitable end trunnions 13 journaled in brackets 14 suitably secured to the bottom 10 of the box at the ends thereof.

15 A pair of background-forming screens 15, 16 of suitable flexible, opaque sheet material are attached in any suitable manner at one end thereof to the rollers 11, 12, respectively, to be rolled up thereby or unrolled therefrom. The other end of each screen 15, 16 is anchored in the longitudinal center of an edge strip 17 of wood, or the like, provided in one face and adjacent each end 20 thereof with a pair of sockets 18, the sockets of each pair being arranged upon opposite sides of the screen. A coil spring 19 is suitably arranged in each roller 11, 12 to rotate the roller in a direction to wind or roll up the screen thereon.

25 Each side wall 3, 7 of the box is provided on the inner face thereof with a pair of vertical, internally threaded, tubular keepers 20 arranged adjacent opposite ends of the box above the rollers 11, 12 and the purpose of which will presently appear.

30 For use selectively with the screens 15, 16, a pair of extensible telescopic supports are provided, one of which is shown in Figures 5 and 7. The supports each comprise a tubular bottom section 21 having a threaded lower end 22 for turning into one of the keepers 20, and a rod section 23 slidably mounted in the other end of the same for adjustment into different set positions established by a set screw 24. The upper, or outer, end of the rod 23 is designed to fit in the sockets 18 of the strips 17.

35 One of the screens may be provided with a white side and a black side, the former for use as a white background, also as a moving picture screen and the latter for use as dark background for photography, and the other screen may be designed to present a pleated black and white side 25 for photography and a differently colored and figured side for a like purpose.

40 In using the described invention, with the box 1 deposited on a floor, or the like, the brace bars 8 swung to extend from the bottom of the box 1, in the manner already described, and the lid 2 opened, the screen 15, 16 appropriate for the occasion is selected and the lower ends 22 of the

sections 21 of the pair of supports turned into the keepers 20 at the side of the box 1 which will be disposed in the rear of the screen when the latter is drawn upwardly. The screen selected is then unrolled by pulling upwardly on the edge strip 17, and said strip affixed to the upper ends of the rod sections 23 of said supports by inserting said ends into the sockets 18 at opposite ends of the strip 17 on the appropriate side of the screen to dispose the supports in the rear of the screen. The rod sections 23 of the supports may then be adjusted upwardly to extend the screen upwardly to the desired height. By lifting the strip 17 off the rod sections 23 and letting go of the strip, the screen may be wound up on the roller, under the influence of the associated spring 19, to house the screen and strip in the box 1. The supports may then be detached from the keepers 20, contracted by adjusting the sections 23 into the sections 21, and deposited in the box 1 for safe keeping. With the lid 2 closed and latched, and the brace bars 8 swung under the bottom of the box 1, the entire apparatus is conditioned for storage or easy carrying as part of a photographer's equipment.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In apparatus of the class described, a box-like base structure, a pair of rollers rotatably mounted therein to extend longitudinally thereof along opposite sides of the same, a pair of flexible sheets of material attached to said rollers, respectively, for unrolling therefrom into upright position, selectively, and means to sustain the selected sheet in upright position comprising a single pair of supports, and means to attach said pair of supports to either side of the structure.
- 5 2. In apparatus of the class described, a box-like base structure, a pair of rollers rotatably mounted therein to extend longitudinally thereof along opposite sides of the same, a pair of flexible sheets of material attached to said rollers, respectively, for unrolling therefrom into upright position, selectively, and means to sustain the selected sheet in upright position comprising a pair of telescopic sectional supports, keepers on said structure for holding said supports upright and arranged in pairs at opposite sides of the structure for selection of a pair on the same or opposite side of the structure as the roller from which the sheet is selected, and means on one end of the selected sheet to attach the same to said supports comprising a flat strip having said end of the selected sheet fixed thereto in the longitudinal center thereof and sockets therein upon 15 opposite sides of the sheet for fitting over the upper ends of the supports when the latter are arranged in either pair of keepers.
- 10 3. In apparatus of the class described, a box-like base structure, a pair of rollers rotatably mounted therein to extend longitudinally thereof along opposite sides of the same, a pair of flexible sheets of material attached to said rollers, respectively, for unrolling therefrom into upright position, selectively, and means to sustain the selected sheet in upright position comprising a pair of telescopic sectional supports, keepers on said structure for holding said supports upright and arranged in pairs at opposite sides of the structure for selection of a pair on the same or opposite side of the structure as the roller from which the sheet is selected, and means on one end of the selected sheet to attach the same to said supports comprising a flat strip having said end of the selected sheet fixed thereto in the longitudinal center thereof and sockets therein upon 20 opposite sides of the sheet for fitting over the upper ends of the supports when the latter are arranged in either pair of keepers.
- 25 4. In apparatus of the class described, a box-like base structure, a pair of rollers rotatably mounted therein to extend longitudinally thereof along opposite sides of the same, a pair of flexible sheets of material attached to said rollers, respectively, for unrolling therefrom into upright position, selectively, and means to sustain the selected sheet in upright position comprising a pair of telescopic sectional supports, keepers on said structure for holding said supports upright and arranged in pairs at opposite sides of the structure for selection of a pair on the same or opposite side of the structure as the roller from which the sheet is selected, and means on one end of the selected sheet to attach the same to said supports comprising a flat strip having said end of the selected sheet fixed thereto in the longitudinal center thereof and sockets therein upon 25 opposite sides of the sheet for fitting over the upper ends of the supports when the latter are arranged in either pair of keepers.
- 30 5. In apparatus of the class described, a box-like base structure, a pair of rollers rotatably mounted therein to extend longitudinally thereof along opposite sides of the same, a pair of flexible sheets of material attached to said rollers, respectively, for unrolling therefrom into upright position, selectively, and means to sustain the selected sheet in upright position comprising a pair of telescopic sectional supports, keepers on said structure for holding said supports upright and arranged in pairs at opposite sides of the structure for selection of a pair on the same or opposite side of the structure as the roller from which the sheet is selected, and means on one end of the selected sheet to attach the same to said supports comprising a flat strip having said end of the selected sheet fixed thereto in the longitudinal center thereof and sockets therein upon 30 opposite sides of the sheet for fitting over the upper ends of the supports when the latter are arranged in either pair of keepers.

ARNOLD BERT COLEMAN.
